(57) **CLAIM**

The ornamental design for a stair handrail, as shown and described.

DESCRIPTION

FIG. 1 is a rear, right, and bottom perspective view of a stair handrail, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1; and,

FIG. 9 is a partial enlarged view of an area labeled 9 in FIG. 2.

The dot-dash broken lines delineate the outer limits or portions of the stair handrail shown enlarged and form no part of the claimed design.

In addition, the dot-dash broken lines in the drawings illustrate an enlarged portion of the design.
